UNITED STATES PATENT OFFICE.

EDWARD P. WAGGONER, OF SYRACUSE, NEW YORK, ASSIGNOR TO THE
A. A. GRIFFING IRON COMPANY, OF JERSEY CITY, NEW JERSEY.

DESIGN FOR A BOILER-PLATE.

SPECIFICATION forming part of Design No. 30,246, dated February 21, 1899.

Application filed January 2, 1897. Serial No. 617,848. Term of patent 14 years.

To all whom it may concern:

Be it known that I, EDWARD P. WAGGONER, of Syracuse, in the county of Onondaga, in the State of New York, have invented and produced a new and useful Design for Boiler-Plates, of which the following is a specification, reference being had to the accompanying drawings, showing a part thereof.

Figures 1 and 2 are respectively front and rear perspective views of a boiler-plate embodying my design.

The leading feature of my design consists of substantially flat front and rear walls and top and bottom walls extended or curved toward each other from substantially their central portions and united at the opposite sides of the boiler-plate.

a a' are the front and rear walls, and *a² a³* the top and bottom walls, of a boiler-plate A embodying my design. Said front and rear walls *a a'* are substantially flat, and their upper and lower portions are provided with circular openings *a⁴*. The top and bottom walls *a² a³* are extended or curved toward each other from substantially their central portions *a⁵* and are united at the opposite sides *a⁶* of the boiler-plate.

The upper part of the plate A is provided

with passages *a⁷*, which extend from front to rear thereof in substantially horizontal series 30 one above the other, and are formed of greater height than width and with rounding upper and lower ends. The lower part of said plate is provided with a passage *a⁸*, which extends from front to rear thereof, and is formed with 35 a substantially horizontal upper edge having transverse corrugations *a⁹* and a lower edge extended or curved upwardly from substantially its central portion toward the opposite ends of said upper edge.

A boiler-plate embodying my design presents a characteristic and pleasing appearance owing to the combined effect of the straight and curved surfaces thereof.

What I claim is—

The design for a boiler-plate, substantially as shown and described.

In testimony whereof I have hereunto signed my name, in the presence of two witnesses, at Jersey City, in the county of Hudson, in the State of New Jersey, this 16th day of December, 1896.

EDWARD P. WAGGONER.

Witnesses:

N. R. MARVIN,
J. M. C. THOMAS.
